DESIGN FOR A KNITTED BLOUSE OR SIMILAR ARTICLE

Hans Boepple, Valley Cottage, N. Y.

Application January 18, 1940, Serial No. 89,529

Term of patent 3½ years

To all whom it may concern:

Be it known that I, Hans Boepple, a citizen of the United States, residing in Valley Cottage, county of Rockland, State of New York, have invented a new, original, and ornamental Design for a Knitted Blouse or Similar Article, of which the following is a specification, reference being had to the accompanying drawing, forming a part thereof.

The figure is a front view of a knitted blouse showing my design.

The design is shown on the dark background in order to bring out the details thereof.

The characteristic feature of my design resides in the combination, on the open work knit blouse disclosed, of frills appliqued along one edge of the front in the manner and position shown in association with a frill collar, all as shown.

The back of the blouse is of one piece and consists of the open work knit shown.

I claim:

The ornamental design for a knitted blouse or similar article, as shown and described.

HANS BOEPPLE.
